UNITED STATES PATENT OFFICE.

CORNELIUS J. BROSNAN, OF SPRINGFIELD, ASSIGNOR TO THE PENINSULAR NOVELTY COMPANY, OF BOSTON, MASSACHUSETTS.

BUTTON-CHUTE.

SPECIFICATION forming part of Letters Patent No. 425,928, dated April 15, 1890.

Application filed August 6, 1887. Serial No. 246,293. (No model.)

To all whom it may concern:

Be it known that I, CORNELIUS J. BROSNAN, of Springfield, county of Hampden, and State of Massachusetts, have invented an Improvement in Raceways or Guides for Button-Setting Tools, of which the following description, in connection with the accompanying drawings, is a specification, like letters on the drawings representing like parts.

This invention relates to raceways or guides for button-setting tools or machines, the main object of which is to provide for the proper delivery of fasteners with their connected buttons, one at a time, to the button-setting devices of such tools or machines. To this end I provide a raceway or guide of peculiar construction, the essential purpose of which is to receive a fastener with its connected button, or a succession of fasteners with their connected buttons, and properly guide it or them in succession to the button-setting devices of button-setting tools or machines, and by the construction of which the said fastener or fasteners will be prevented from turning about or becoming displaced therein.

My invention consists, primarily, of what I here term for convenience a "raceway or guide," preferably formed from sheet metal, and having an opening to receive the body or main portion of the fastener, and a slot to receive the shank-eye of the button, which may be connected with the fastener, and two grooves to receive the legs or points of the fastener, substantially as hereinafter fully described, and particularly pointed out in the claims.

Figure 1 is a perspective view of a raceway embodying my invention; Fig. 2, a section thereof on line xx , Fig. 1. Fig. 3 shows one form of fastener which may be employed with the raceway or guide shown in Fig. 1. Fig. 4 shows said fastener with connected button in the raceway or guide. Fig. 5 is a modification to be referred to; and Fig. 6 is a modification showing the slot for the eye of the button centrally disposed in the raceway, as in the case where a common staple-fastener is to be guided in said raceway.

The raceway or guide A, preferably struck up from sheet metal, is provided with an opening a to receive the body or main portion of

the fastener to be contained therein, a slot a' in one side thereof to receive the shank-eye of the button to be connected with the fastener of the style or kind for which the raceway or guide may be specially designed, and with two grooves a^2 a^3 in the side of the raceway or guide opposite that having the slot a' , to receive the legs or points of the fastener and prevent the said fastener from turning about or becoming displaced in the said raceway or guide.

In Fig. 1 I have shown the raceway or guide A as provided at one end with a retaining-spring b to properly hold the raceway or guide to the connecting part of the button-setting machine with which it may be employed; but I do not here wish to be understood as limiting myself to the exact means shown with which to secure it in place in the button-setting machine employing the same, since it is clear that the same may be varied or changed without departing from the spirit of my invention. Further, in said Fig. 1 I have shown the end opposite that having the retaining-spring b sealed or closed, with an end plate c soldered thereto to act as a stiffener and keep the form of the raceway or guide and the size of the slot a' intact. In this case—that is, where the upper end of the raceway or guide is sealed—the fasteners with their connected buttons are fed into said raceway or guide at its bottom end, and when properly filled it is then secured by the spring-plate b to the machine with which it is to be employed.

It will be noticed from an inspection of Fig. 2 that in the present instance, where the raceway or guide is formed from sheet metal, the two grooves a^2 a^3 are in reality formed by striking in the rib-like portion or saddle d. In this particular instance the raceway or guide is especially adapted to receive and guide the style of fastener shown in Fig. 3, which is one of well-known construction, and the manner in which that fastener with its attached button is placed in the said raceway or guide is shown in Fig. 4.

It will be noticed that to accommodate this fastener the slot a' is placed to one side of the center line (indicated by the dotted lines yy') but with other forms of fasteners the position of the slot may be varied to suit.

I do not wish the scope of my invention to be limited to the exact construction shown, or by whatever terms I have used to designate the same, since the form and size may be varied in many respects to adapt it to the use therewith of various styles of fasteners, and there are many terms which may be used to designate the device embodying said invention.

- 10 Fig. 5 shows a raceway or guide in which the plate *c* is dispensed with to allow the fasteners to be fed therein from either end of the said raceway or guide.

15 Although the raceway or guide herein shown and described is often employed in machines or tools for setting buttons in such manner, that the side or wall thereof containing the slot *a'* is disposed uppermost and at other times undermost, as compared with that 20 wall or portion having the grooves *a²* *a³*, yet for identification and convenience the wall having the slot *a'* may be, and now is, called the "top" of the raceway and that wall or portion having the grooves *a²* *a³* the "bottom" of 25 said raceway.

30 As shown in the drawings, the slot *a'* is cut or made entirely in the top of the raceway and is independent of its side walls or portions, and necessarily so to adapt it as a guide 35 or raceway for button-fasteners carrying shank-eye buttons.

I am aware of the patent to H. C. Bradford, No. 124,029, granted February 27, 1872, which shows a raceway or guide for button-hooks, and I make no claim to anything 35 therein set forth.

I claim—

1. A raceway or chute for fasteners carrying eye-shank buttons, having a top, bottom, and two side walls, the said side walls being 40 substantially uniform in height, the top wall having a slot extending lengthwise of the raceway and intermediate of said side walls, and the bottom having an interiorly-projecting rib or saddle, leaving a channel at each 45 side thereof for the legs of the fastener, and a space above said saddle and beneath the slotted top to accommodate the shank-eye of the button, substantially as and for the purpose set forth.

50 2. A button-chute having bottom and side walls and a slotted top, the bottom being struck up to form a saddle, leaving a channel at each side for the legs of the fastener, and a space above the saddle and beneath the slotted top for the shank of the button, 55 substantially as described.

3. A one-piece sheet-metal button-chute having closed bottom and side walls, a slotted top, the bottom being struck up to form a 60 saddle, leaving a channel at each side thereof for the legs of the fastener, and a space above the saddle and below the slotted top to accommodate the shank-eye of the button, substantially as described.

65 In testimony whereof I have signed my name to this specification in the presence of two subscribing witnesses.

CORNELIUS J. BROSNAN.
